UNITED STATES PATENT OFFICE.

THEODORE C. SMITH, OF PHILADELPHIA, PENNSYLVANIA.

LUMINOUS PILE.

1,394,449.

Specification of Letters Patent. Patented Oct. 18, 1921.

Application filed October 12, 1920. Serial No. 416,545.

To all whom it may concern:

Be it known that I, THEODORE C. SMITH, a citizen of the United States, residing at Philadelphia, in the county of Philadelphia 5 and State of Pennsylvania, have invented new and useful Improvements in Luminous Piles, of which the following is a specification.

My invention relates to a luminous pile, 10 and has for its object to provide means for holding a self-luminous material such as radium powder in a dry state beneath a transparent member, said means preventing the displacement of the self-luminous material.

Another object of the invention is to provide a luminous pile fabric consisting of a retaining member of suitable material.

Another object of the invention is to provide a luminous pile consisting of a retaining member of suitable material having a nap, a dry self-luminous material immeshed in the nap of the retaining member and a transparent member covering said self-luminous material and in contact with the nap of the retaining member, said retaining member when flexible having a backing member for adding stiffness thereto.

A further object of the invention is to 30 construct a luminous pendant of the pile fabric above referred to.

A still further object of the invention is to provide a luminous pile which consists of a self-luminous powder sprinkled upon a material having a nap, such as felt; matting or packing the self-luminous material so it becomes immeshed in the nap and a transparent member placed over the self-luminous powder so as to engage the nap and cause 40 the different elements thereof to entwine each other and the particles of the self-luminous powder to prevent displacement of the latter.

With these ends in view, this invention 45 consists in the details of construction and combination of elements hereinafter set forth and then specifically designated by the claims.

In order that those skilled in the art to 50 which this invention appertains, may understand how to make and use the same, I will describe its construction in detail, referring by numerals to the accompanying drawing forming a part of this application, in 55 which:—

Figure 1 is a side elevation of a pendant

and a ball link chain to which it may be fastened, portions being broken away and shown in section to illustrate one form of producing the luminous pile. 60

Fig. 2 is a sectional view of a different formation of the luminous pile.

Fig. 3 is a face view of another formation.

Fig. 4 is a transverse sectional view thereof. 65

In the use of a self-luminous material the same is generally mixed with an adhesive and pasted or painted upon an object and it has been found the brightness of the material when so mixed is usually only twenty-five per cent. of that of the dry material and the material when mixed with an adhesive also decreases in brightness at a much higher rate than does the dry material of the same brightness so that by using the 75 self-luminous material in the dry state its highest efficiency may be maintained and by the use of my invention I can provide a surface of the self-luminous material without the use of an adhesive or other liquid and 80 element and can utilize the same in producing pendants designating slides or signs, dial faces for instruments and the hands and pointers of such instruments. 85

In Fig. 1, I have shown a pendant comprising a transparent facing 2 the same being in this particular case a cup shaped member of glass having an external flange 3 and within this transparent face is located the retaining member 4 of some suitable 90 material having a nap in which is immeshed a self-luminous material 5 such as radium powder in its dry form, said powder being prevented from displacement by the entangling of the nap elements about one another 95 and the particles of powder within the retaining member 4 is forced into close proximity with the transparent facing 2 by means of a suitable backing member 6 such as cork or other suitable solid or semi-solid 100 object or substance, while the top of the transparent face or the open end thereof is hermetically sealed by a suitable layer of material 7 such as wax or paraffin. 105

To complete the pendant, I provide a dome or bell shaped metallic cap 8 preferably of brass secured to the transparent facing by rolling or crimping the edge thereof about the external flange 3. This cap is provided with an opening 9 of slightly larger diameter than the balls 10 of the ball chain to which the pendant is adapted to be attached. 110

From this opening leads a slot 11 to the top of the cap, said slot being of sufficient width to accommodate one of the wire links 12 of the chain so that to place the pendant upon the chain it is only necessary to insert the end ball of the chain through the opening 9 and bring the wire link 12 into registration with the slot 11 and moving said link through said slot until it assumes the position herein illustrated after which the material of the cap at each side of the slot may be pinched or forced inward so that the major portion of said slot or that part unoccupied by the link will be of smaller width than the diameter or thickness of the wire link which will prevent accidental withdrawal of the link from said slot thus fastening the pendant to the chain.

When the luminous pile herein described is used with pendants of this character the life of the pendant will be much longer and the brightness much greater so as to be discernible at greater distances and where said pendants are used to designate positions of pull chains on electric light fixtures and the like such pull chains may be readily located in the darkness.

In Fig. 2, I have shown the luminous pile consisting of a backer or backing member 13 disposed across the retaining member 14 at least one face of which is provided with a nap for holding the self-luminous material or powder 15, while across the retaining member with the powder immeshed is a transparent member 16, all of said members being held together by some suitable clamping means 17 here shown as forming a part of the backing member with one edge crimped or rolled over the transparent member. The transparent member may be of glass or celluloid and when the luminous pile is made in this form it may be utilized as a dial face for instruments such as those used by naval and military officers as well as time pieces or it may be used as a sign or designating slide such as are used in apartment houses or the like for indicating certain mail boxes or bells, the information desired to be imparted being written across the transparent member.

In Figs. 3 and 4, I have shown a slightly different form of formation in which the transparent member 18 and the retaining member 19 with the nap toward the transparent member and the self-luminous pow-

der 20 therebetween are fastened together along their edges as by stitches 21.

As above stated the self-luminous material such as radium or other powders having a radioactive constituent can be used in its dry state and without mixing it with some other element that reduces the radiation of such materials and the life of such materials is prolonged and the brightness retained, and I have found that by producing a luminous pile as above described I obtain all the advantages of all the luminous material in its dry state.

Although I have described my invention as embodying the retaining member such as felt having a nap it is to be readily understood that other materials may be used having a finely divided surface for the retention of the powder particles some of such other materials being crape paper the fibers of which produce a nap, while the cellular surface would also retain some of the particles; straw board on which a nap has been raised by finely cutting the surface or any cloth having a rough surface, and it is to be understood that where I refer to a nap it relates to any surface which will retain powder particles particularly when held in close proximity to a transparent member.

Of course I do not wish to be limited to the exact details of construction as herein shown as these may be varied within the limits of the appended claims without departing from the spirit of my invention.

Having thus fully described my invention, what I claim as new and useful is:—

1. A luminous pile comprising a retaining member having a nap, a self-luminous material in a dry or powdered state immeshed in said nap and a transparent member disposed across said retaining member and covering the self-luminous material.

2. In a device of the character stated, a transparent member, a retaining member having a nap disposed within the transparent member, a self-luminous material in a dry or powdered state immeshed in said nap and disposed against the transparent member, a backer member for holding the retaining member against the transparent member, and means for hermetically sealing the aforementioned parts.

In testimony whereof, I have hereunto affixed my signature.

THEODORE C. SMITH.
